United States Patent Office

Des. 185,458
Patented June 9, 1959

185,458

PAINT COLOR DISPENSER

Edward C. Morris, Camden, N.J., assignor to Baltimore Paint and Chemical Corporation, Baltimore, Md., a corporation of Maryland

Application September 12, 1958, Serial No. 52,621

Term of patent 14 years

(Cl. D52—2)

Fig. 1.

Fig. 2.

Fig. 2 is a top plan view thereof.

The undisclosed portion of the paint color dispenser is substantially the same in appearance as that shown in Fig. 1 except for the door and trough elements.

What is claimed is:

The ornamental design for a paint color dispenser, as shown and described.
